UNITED STATES PATENT OFFICE.

SAMUEL W. LUITWIELER, OF LOS ANGELES, CALIFORNIA.

CAM-OPERATED PUMP.

No. 926,267.

Specification of Letters Patent.

Patented June 29, 1909.

Application filed March 21, 1905. Serial No. 251,494.

To all whom it may concern:

Be it known that I, SAMUEL W. LUITWIELER, of the city of Los Angeles, in the county of Los Angeles, in the State of California, pump manufacturer, have invented 5 certain new and useful Improvements in Cam-Operated Pumps for Raising and Distributing Water, of which the following is a full, clear, and exact description or specification, reference being had to the annexed drawings and to the letters marked thereon.

My said invention which relates to certain improvements in pumps for raising and delivering water, is a further development of 15 earlier inventions relating to certain cam driven pumps for which Letters Patent have been applied for, by and granted to myself, the said SAMUEL W. LUITWIELER, No. 676,542, dated June 18th 1901; and certain cam 20 mechanism for producing reciprocating motion, in respect of which, application for Letters Patent was duly made by myself and M. L. Wilkinson, on the 16th day of May, 1898, and assigned in respect of the whole of 25 his rights or interest in the said invention and Letters Patent by the said M. L. Wilkinson to and in favor of myself exclusively, and issued to myself, the said SAMUEL W. LUITWIELER, as Letters Patent No. 629,039, 30 dated July 18, 1899.

My present invention has for part of its object to provide vertical stationary guide-ways at the rear of the cam-frames in which guide-ways the slide-blocks forming part of 35 the rear of each cam-frame fit, so that each cam-frame may be reciprocated smoothly and with requisite vertical guide support therein. The cam-frames as I now construct them, provided as aforesaid with slide-blocks 40 at the rear of each and near to the edges thereof, fit into the two inner or adjacent vertical guide-ways which are situated in the front face of a vertical column or pillar at the rear of the framing, otherwise known 45 as housing, wherein the entire pumps and their connections are carried; and the outer slide-blocks of the cam-frames, both at the rear as well as at the front of the cam-frames fit into and operate in parallel vertical 50 guides, at the rear and front of the end frames or housings of the pump respectively. In this improved arrangement of both the 55 guide-ways and slide-blocks of the cam-frames, not only are the cam-frames during operation much more effectively supported than hitherto, by the slides being at farther

distances apart and in greater numbers with larger sliding faces, but they are also supported completely, both at the front, the rear, and laterally during every position of 60 the cam-frames, thereby insuring steadiness of sliding movement during the pump's operation.

My said invention has for the other part of its object to enable two or more cam-driven pumps of the class hereinbefore referred to, to be driven directly by means of a crank and connecting rod, from a steam, gas, or other reciprocating engine, operating a crank shaft, and with constant load and 65 speed.

In the operation of all other reciprocating pump mechanisms of which I am at present aware, the water is discharged from the pumps in pulsating or irregular flow. Owing to the continuity or regular discharge 70 of water from the class of cam driven pumps to which this invention relates, I am enabled to drive the pumps with toothed gearing placed in part upon a crank shaft 75 having the crank on that part of the shaft between the housings.

Upon the annexed drawings, Figure 1, is a front elevation of the driving mechanism for operating a double plunger pump 80 constructed in accordance with my present improvements. Fig. 2, is a part plan of the same, and Fig. 3 is a central transverse section thereof showing some parts in elevation and as driven by a crank instead of by a 85 belt pulley as in Figs. 1 and 2. The frame or housing of the improved pump includes a base, S, and uprights, T, T, rising one at each side of the base, said uprights being connected at their upper ends by a cross-bar, 90 V. The vertical guide-ways A, are mounted upon the inner sides of the uprights T, T, near the front edges of the latter, are provided with L-shaped flanges, a, best seen in Fig. 2, and said guide-ways are those against 95 and within which the front bearing blocks B, of the cam-frames C, operate, and the vertical guide-ways D, are those against 100 and within which the rear bearing faces F, F', of the said cam-frame C, also operate, 105 by being alternately reciprocated upward and downward therein, coincidently with the rotations of the cams E, and E', respectively. Both of the cams E, and E', are carried on one and the same cam shaft E'', 110 and have their driving surfaces G, G, continuous. These driving surfaces G, G, oper-

ate upon the antifriction rollers H, in the upper part of the cam-frames C, and produce the lifting strokes of the cam-frames C, C, and of the inner and outer pump rods I, and I', respectively, attached to the upper offset J, of one cam-frame C, and to the lower offset J', of the other cam-frame C, as is well understood in the class of pumps to which my present invention relates, and 10 as shown upon the drawings. The downward strokes of the pump are produced by a second driving surface K, provided on that part only of each cam E, and E', which is about opposite to the maximum radius of 15 the lifting surfaces G, G, as shown by the drawings, and this portion K, of each cam, acting upon the lower antifriction rollers L, at each downward stroke of the cam-frames E, and E', produces the downward stroke 20 of each pump rod I and I', (because of the contour of the portions K,) in less time than the upward strokes of the pump are made by the lifting surfaces G, G, of these cams.

Since the cams E, and E', are by reason 25 of the construction which has been herein described of equal dimension and contour of their respectively opposite driving surfaces and structure—it follows that by keying these cams on to the cam shaft E'', in such 30 positions that their maximum and minimum diameters are opposite each other, that the cams are balanced in whatever position of rotation they may be situated, and that as the cam-frames C, C, and the parts carried 35 thereby are of equal weight, the parts are always in equilibrium during their rotation, which is effected by the shaft M, and spur pinion N, acting upon the spur wheel O, upon the cam shaft E''.

40 While in Figs. 1 and 2, I have shown my improved pump as being driven by a belt pulley P, it is to be understood that I prefer to dispense with the said belt pulley, and to substitute therefor, the crank Q, shown at 45 Fig. 3, to which crank I couple the connecting rod of a steam or gas engine, and drive the pumps directly either by such engines or other motor operating directly upon a crank.

50 It is further to be understood that the vertical slides D, against and within which the central sliding blocks F, at the rear of the cam-frames C, C, operate, are formed on the front part of the column R, as shown in 55 the drawings; the column R, being firmly bolted to the base-plate S, of the framing or housing at the rear of said base plate, intermediate the uprights T, and to an upper cross bar V, of the housing which connects 60 the uprights T, T as shown in the drawings at Figs. 1 and 2 but broken out in Fig. 2. In the case of pumps of comparatively small dimensions the outer rear slides D, shown in Fig. 2 may be dispensed with, in which case 55 the cam-frames C, are guided by and within

the front slides A, and the central rear slides D, in the column R.

In cases wherein it is desired to employ a vessel of compressed air, as is sometimes resorted to in connection with pumps, the 70 hollow of the column R, may be utilized for that purpose by connecting it through a passage U, with the pump as shown at Fig. 3, in which case the column R, may be employed for an additional useful purpose besides that of constituting the central guide-ways for the rear slide-blocks of the cam-frames C. 75

Having now described the nature of my said invention and the best system, mode, or 80 manner I am at present acquainted with for carrying the same into practical effect, I desire to observe in conclusion that what I consider to be novel and original and therefore claim as the invention to be secured to me 85 by Letters Patent is as follows:

1. In a pump of the class described, a frame or housing comprising a base, uprights rising at the sides of the base, a cross-bar connecting the upper ends of said uprights, and a pillar or column mounted upon and rising from the rear part of the base in rear of and intermediate the uprights and connected at the front edge of its upper end with the cross-bar connecting said uprights, 90 vertical guide-ways upon the uprights and upon the intermediate column, and reciprocating cam-frames, each having slides engaging guide-ways upon the uprights and upon the intermediate column. 95

100 2. In a cam-driven pump of the class described, a frame or housing comprising a base, uprights rising at the sides of the base, a cross-bar connecting the upper ends of said uprights, and a pillar or column mounted upon and rising from the rear part of the base in rear of and intermediate the uprights and connected at the front edge of its upper end with the cross-bar connecting said uprights, vertical guide-ways upon the inner 105 sides of the uprights near their front edges said guide-ways having L-shaped flanges, guide-ways upon the uprights near their rear edges, guide-ways upon the face of the intermediate column, and reciprocating cam-frames, each having slides engaging guide-ways near the front and rear edges of the uprights and upon the face of the intermediate column, said column being closed at 110 its upper end, and there being an air inlet 115 port formed through the base, and a pump cylinder located beneath said base, said port establishing communication between said cylinder and the interior of the column, said column being also in the rear of the cam 120 frames. 125

3. In a cam-driven pump of the class described, a frame or housing including a base, uprights rising at the sides of the base, a column rising from the rear of the base in 130

rear of and intermediate the uprights, and a cross-bar connecting the upper ends of the uprights and connected with the front edge of the top of the intermediate column, in combination with reciprocatory cam-frames gilded between the uprights and the column.

In testimony whereof I, the said SAMUEL

W. LUITWIELER, have hereunto set my hand and seal before the two subscribing witnesses.

SAMUEL W. LUITWIELER. [L. S.]
